(57) **CLAIM**

The ornamental design for a sippy cup, as shown and described.

DESCRIPTION

FIG. 1 is a top isometric view of a sippy cup showing our new design;

FIG. 2 is a left side view of the sippy cup of FIG. 1;

FIG. 3 is a right side view of the sippy cup of FIG. 1;

FIG. 4 is a front view of the sippy cup of FIG. 1;

FIG. 5 is a rear view of the sippy cup of FIG. 1;

FIG. 6 is a top view of the sippy cup of FIG. 1; and,

FIG. 7 is a bottom view of the sippy cup of FIG. 1.

The broken lines in the drawings depict portions of the sippy cup that form no part of the claimed design.
